DENTAL MODEL ARTICULATOR

Ralph A. Pittman, Eldorado, Ark., and Joseph
A. Gardner, Memphis, Tenn.

Application November 4, 1935, Serial No. 48,144

2 Claims. (Cl. 32—32)

This invention relates to improvements in a device for holding molds in which models of portions of the human teeth and jaws may be cast and after the casting of such models they may be 5 articulated.

It particularly relates to an articulator from which the models may be removed in order that they may be worked on or reproduced and in which the models themselves or reproductions thereof 10 may again be secured, and removed as often as it may thereafter be found necessary.

The invention also relates to means by which the parts of the articulator may be relatively adjusted in order to provide desired positioning of 15 the mold with reference to the articulator and to provide such other adjustments of the parts as may be necessary or desired to properly position them during the model casting operation, and thereafter to properly articulate the models 20 themselves.

The primary object of the invention is to provide a model holder in which the models are directly mounted in such manner that either or both may be removed and replaced, such number 25 of times as may be desired without the removal with the models of any part of the holder itself.

A further object of the invention is to provide a model holder in which one of the holder parts may be shifted laterally with regard to the other 30 thereof to provide proper articulation of the models.

A further object is to provide a simple and effective mold holder which may be readily adjusted vertically and which also may be tilted 35 out of horizontal to align the mold.

The means by which the foregoing and other objects are accomplished and the manner of their accomplishment, will readily be understood from the following specification on reference to the 40 accompanying drawings, in which,—

Fig. 1 is a side elevation of the articulator with a mold and models therein.

Fig. 2 is a plan view of the articulator with mold and models removed.

Fig. 3 is a section taken on the line III—III of 45 Fig. 2.

Fig. 4 is a section taken on the line IV—IV of Fig. 1, and

Fig. 5 a sectional elevation taken on the same 50 line looking in the direction of the arrows, but with the mold and models removed.

Fig. 6 is a plan view of a modified form of upper model holder.

Fig. 7 is a sectional side elevation taken as on 55

line VII—VII of Fig. 9, showing a slightly modified form of the device with the mold in place.

Fig. 8 is a corresponding end elevation.

Fig. 9 is a plan view.

Fig. 10 is a sectional plan taken on the line 5 IX—IX of Fig. 7 with the mold removed.

Referring now to the drawings in which the various parts are indicated by numerals, 10 is an upper holder and 11 a lower holder. From the lower holder a pair of arms 12 extend upwardly 10 and rearwardly and are provided at their upper ends with bosses 13. 14 is a plate which lies between the bosses 13 and is pivotally secured thereto by screws 15, which preferably are thumb screws having knurled heads, and having coned 15 points which enter complementary recesses in the ends of the plate 14 to provide pivotal engagement. The rear end portion 16 of the upper holder 10 overlies the plate 14 and is oscillatably secured thereto by a clamping screw 17 and 20 thumb nut 18. Secured in the portion 16 of the holder 10, are pins 19 which are laterally displaced from the screw 17, these pins extending into arcuate grooves 20 in the plate 14 and cooperating therewith to limit the oscillation of the 25 holder. The forward portions of the upper holder 10 and the lower holder 11, are each formed by two prongs 21, 22 which are spaced apart throughout their length and which have opposed inner edges or faces which converge rearwardly. In 30 cross section these inner edges of the upper prongs are bevelled, forming downwardly converging faces whereas the inner edges of the lower prongs which are also bevelled, converge upwardly. The upper holder 10 is provided with an 35 opening 23 separated from the inner ends of the prongs by a bar 24 through which opening a suitable tool may be inserted to exert a prying action on the back end of a model held by the prongs and thereby to effect the disengagement of such 40 model. The lower holder 11 may be provided with a similar opening should it be so desired.

In Fig. 6 a modified form of upper holder is shown in which a single central prong 21A is substituted for the two prongs of the preceding 45 figures, the outer edges of this prong diverging rearwardly and being bevelled, these bevels diverging downwardly in order to hold a model thereon. The lower holder may of course be similar.

Extending upward from the lower holder 11 approximately at the junction of the part 12 therewith, is a slotted post 25 against which a post mold retainer 26 is secured as by a screw 27 and a nut 28, the nut 28 preferably having an 55

elongated body and a knurled portion 29 usable in engaging and disengaging it. The retainer 26 has oppositely disposed prongs 30, 31 which are adapted to lie on opposite sides of a mold 5 which is to be held thereby. The retainer is ordinarily positioned as shown in Fig. 5 with its prongs 30, 31 horizontally opposite. It may be raised or lowered by loosening the nut 28 and sliding it upward or downward in the slot in the post 25. Also the prongs may be rocked about the screw 27 as an axis to raise or lower one prong relative to the other thereof and thereby be adapted to receive a distorted or twisted mold and hold it in a particular position or alignment, or to adjust such alignment. 32 is a screw preferably having a knurled head which screw is threaded through the upper holder 10 and which projects below this holder into engagement with the upper end of the post 25. 20 33 is a jamb nut on the screw 32. The screw 32 forms a support for supporting the upper holder 10 with respect to the lower holder 11 and provides means for adjusting the relative positioning thereof. The mold which is of usual 25 type ordinarily comprises a bite-tray formed of two spaced side members 34, which members ordinarily are made of this comparatively stiff pasteboard and are secured together adjacent their horizontal mid-portions by a diaphragm of 30 strong cloth 35 ordinarily secured to the paper sides by stitching. 36, 37 are respectively the upper and lower wax mold portions which are retained by the side members 34 and separated by the cloth diaphragm 35. 38 and 39 are respectively the upper and lower models which are formed in the wax portions 36, 37 of the mold and which models are removably held by the holders 10 and 11.

In Figs. 7 to 10 inclusive, 50 is the upper holder 40 and 51 the lower holder, the rear end of which lower holder is bent upward to form a slotted post 52, this slotted post adjustably carrying a mold retainer which includes a threaded rod 53 having at its forward end oppositely extending fingers 54, the rods extending through a threaded sleeve 55, thence through the slotted post 52 and being clamped to the post by a knurled nut 56.

It will be particularly noted that the sleeve 50 55 may be adjusted along the rod 53 to advance the fingers 54 further from or closer to the post 52, as may be desired; that the rod may be raised and lowered and clamped at desired height in the slotted post and may be turned about its longitudinal axis to regulate the positioning of the fingers 54. At its upper end the post 52 is bent horizontally to form a continuation or portion 57. 58 is a bolt secured in the horizontal portion 57 and extending vertically upward 60 therefrom. On this bolt is turnably mounted a member 59 which member is adapted to be clamped against the horizontal portion 57 by a nut 60 and lock nut 61. The horizontal portion 57 has in its upper surface an arcuate groove 65 62 which is provided with a deeper depression 63 in alignment with the longitudinal axis of the lower holder. The member 59 is chambered out to provide a recess 64 in which is disposed a compression spring 65 which acts to push a 70 pin 66, having a rounded end, downward, this pin being held in engagement with the slot 62 by the downward pressure of the spring and being adapted to engage the ends of this slot to limit turning movement of the member 59 and 75 additionally to engage the center depression 63

of the slot, it being understood however that the pin may be moved out of engagement with this central depression by turning pressure of the member 59. The upper holder 50 is provided at its rear end with two arms 70 each having a boss 71 through which screws 72 extend to provide pivotal engagement of the holder arms with the member 59.

The holders 50 and 51 as before, are provided with prongs 73, 74, respectively, having inner 10 faces which converge rearwardly and are shaped in cross section as before. The converging faces of these arms are preferably stepped apart toward their outer ends, shoulders 75, 76 being formed at the junction of the two face sections against which the model is formed and against which it abuts when being replaced after removal. These shoulders perform in this respect the same function for a transversely disposed model that the bottom 77 of the slot performs for a longitudinally disposed model, or that the shoulders 78 of Fig. 6 perform.

The outer ends of the prongs 73 are joined by a transverse bar 80 which carries at its center a hollow boss 61 through which is slidably disposed a post 82, this post being adjustably secured by a set screw 83. The outer end of the lower prongs 74 are joined to and carry a transverse plate 84 having an inclined upper face 85 on which the lower end of the post 82 rests. The upper holder may also be tapped toward the rear end, but forward of the bolt 58, to receive an adjusting screw 90, the lower end of which screw rests on an inclined portion 91 of the lower holder. The screw 90 and the post 82 perform essentially the same service and it will be understood that one or the other may be omitted. Ordinarily the post support is not used with the illustrated narrower type of holders, but is used only with the well known Gysi articulator type patented October 15, 1912, No. 1,041,270 and is introduced for the purpose of showing a closed end holder of this type applicable to an articulator having such a post.

It will be understood that the retainer 26 of Figs. 1 to 5 may be used with this type of holder if a longitudinally disposed mold is to be supported.

In using the device two pieces of suitably prepared tough wax are softened by heating and are placed in the upper and lower sections of the bite tray. This is then placed in the mouth and the teeth are clamped down displacing the wax until the teeth meet as in biting, except that the cloth diaphragm separates them. The softened wax so displaced forms an exact mold of the teeth and the gums thereabove. The teeth are held closed long enough to allow the wax to cool and harden sufficiently to hold its shape, requiring usually about three minutes. Thereafter the mouth is opened and the mold removed, the above being usual practice. The mold so formed is placed between the prongs of the retainer and secured thereto by an easily melted wax 40. The retainer with the mold secured in place is then placed in the model holder, and is adjusted upward or downward along the slotted post 25 to adjust its position relatively to the top and bottom model holder. Should the mold so positioned not properly align with the holder above and below, the retainer may be tilted to one side or the other about the screw 27 as an axis, to secure such alignment and thereafter the clamping nut 28 be tightened to secure the retainer with the mold therein in proper position.

The same procedure is followed with respect to the form of the device shown in Figs. 7 to 10 if a retainer having forked prongs is used. However, if the retainer 53, 54 is used, it should ordinarily be adjusted longitudinally also.

With the mold secured, an investment material such as a specially prepared plaster of Paris or some other of the harder setting materials which are purchasable for this purpose is then mixed to a plastic consistency and the upper mold filled, care being taken that the investment material accurately fills the mold; that the upper portion thereof firmly engages the opposite prongs of the model holder, and against an end 17 or shoulder portion 75 thereof, and that it extends level with, or preferably slightly above the tops of the prongs. When the upper model has set sufficiently to permit, the holder is inverted and the operation repeated for the lower model. After the two models have thoroughly set and hardened a tool may be inserted as in the opening 23 and the models gently dislodged from the prongs of the upper and lower holders. This may be done with the wax mold still in place, or if preferred, the upper holder may be raised with its model and the then accessible mold be removed. In any event the models after very light jarring may be removed from their respective holders and afterwards may be restored therein at any time it should be so desired. When the models have been removed from the holders they may be trimmed up in such manner as may be desired and any desired modifications or changes be made. It will readily be seen that a model may be shifted longitudinally even though the end of the holder be closed as by the bar 80 if space be left as in Fig. 7, and when so shifted may be moved downward from the holder when so shifted. When completed both models are, or either model is turned over to the laboratory to make bridges, plates or the like, as may be desired, and provided the laboratories are equipped with a corresponding articulator, are if and when desired, assembled in such articulator. When the laboratory has completed its work, the models and the completed work are returned to the dentist who may then reassemble the models in his own articulator and do such other work thereon as occasion may require. In such replacement the shoulders 75, 76 or the bottoms 17, 18 of the holders prevent undue wedging of the models in the converging jaws.

It often happens that it is desirable to displace one holder of the articulator laterally with respect to the other. Such displacement may be effected by loosening the thumb nut 18, and after the shift is accomplished retightening it. Also it is found that after the work has been done by the laboratory it is often necessary on

replacing the models in the holders to slightly shift one holder and the model carried thereby with respect to the other holder and its model to make a perfect articulation of the teeth of the two models, and this may likewise be done by loosening and tightening the thumb nut 18.

The thumb screws 32 or 90 or the adjustable post 82, are used primarily in establishing the relative spacing of the upper and lower holders before making the model and after the models are made may be retracted allowing one model to seat on the other, unless one model only is being used.

It is understood that articulators are made to which the model is permanently attached for its life and that articulators are also made having removable parts to which the models are attached. In the first of these cases an articulator must be retired from other use until the model has served its purpose and is destroyed and that the same is true of the removable parts of articulators in which such parts are made a part of the model. These latter also are subject to less and are a constant source of trouble. However the primary advantage of the present device is that models once made may be indefinitely preserved and be at any time available for reuse.

What we claim is:

1. In an articulator for dental models, upper and lower model holders spaced and held apart, and a slotted post adjacent an end of said holders carried by one thereof and projecting toward the other thereof; a mold holder comprising a round, elongated member having prong portions adapted to be engaged with and support a mold for said models, said member being disposed through said slot, and being threaded throughout a major portion of its length, a nut disposed on said threaded portion forming an adjustable abutment adapted to contact one side of said post and a second nut on said threaded portion adapted to clamp said post against said abutment.

2. In an articulator for dental models, an upper model holder and a lower model holder spaced and held apart, said holders each comprising a body portion having prong members extending forwardly therefrom, said prongs having forwardly diverging model engaging surfaces, said body portions each being apertured rearwardly but adjacent the rear ends of said prongs, whereby to permit insertion through said aperture of a model disengaging tool and exertion on said model of a prying strain to disengage said model, said body at the rear edge of said aperture forming an abutment adapted to act as a tool fulcrum.

RALPH A. PITTMAN.
JOSEPH A. GARDNER. 60
